UNITED STATES PATENT OFFICE.

WILLIAM B. LYNCH, OF BROOKLYN, NEW YORK.

SURFACE CLEANER.

Application filed April 15, 1925. Serial No. 23,331.

To all whom it may concern:

Be it known that I, WILLIAM B. LYNCH, a citizen of the United States, and a resident of the city of New York, borough of Brooklyn, in the county of Kings and State of New York, have invented a new and Improved Surface Cleaner, of which the following is a full, clear, and exact description.

This invention relates to surface cleaners, and has for its object the provision of a device having a pair of closely associated concavo-convex flexible members, the cooperating free or working edges of said members exerting varying pressures consecutively on the surface to be cleaned.

Another object of the invention is the provision of a device having a pair of closely associated flexible blades curved rearwardly from the line of action of cleaning so that when the free working edges are applied they will frictionally engage the surface to be cleaned at substantially a right angle to the surface instead of being dragged across said surface and thereby provide for a more thorough cleaning.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a transverse vertical section of the scrubbing head of the mop showing the position of the blades applied to a surface and before the mop is propelled.

Figure 2 is a transverse vertical section of the scrubbing head of the mop showing the position of the blades when in cleaning action.

Figure 3 is a bottom plan view of the head of the mop.

Referring more particularly to the drawings, 10 designates a block forming part of the head which has a flat outer surface, as shown at 11. The inner surface, as shown at 12, may be rounded off in any desired manner, and a passage 13 is provided located centrally of the block and passing entirely

through the same to receive the lower end of 55 the handle 14.

A pair of blades 15 and 16 forming the cleaning elements of my device are secured to the flat surface 11 of the block 10 by means of a cleat 17 and screws 18. The cleat 17 may be made of wood or metal or any other material suitable for the purpose and extends longitudinally of the outer surface of the block and terminates short of the edges of the blades. The cleat is made relatively thin in order not to interfere with the operation of the blades when applied to a working surface 19.

It will be noted that the blades are relatively straight intermediate their ends, and where connected to the block 10 the free projecting portions 20 of the blades are concavo-convex in cross section with the working edges 21 rounded. A wire or cord 22 is inserted between the inner faces of the free portions 20 of the blades and at points where the blades are connected to the block 10 so that the free portions of the blades will be slightly spaced from each other in order to prevent interference of the blades when in operation. A screw 23 is passed through the block 10 and transversely through the lower end of the handle 14 for aiding in securing the handle in position.

In the operation of my device, either of the opposite working edges 21 of the blades are applied to the working surface, as shown in Figure 1, with the blades assuming a position which is directed outwardly from the handle 14 with the rear portions of the working edges resting on the floor. However, when the head is forced forwardly for cleaning the surface, the lower ends of the free portions 20 of the blades will assume a position which is at substantially a right angle 90 to the working surface so that the working edges 21 of the blades will be in direct and frictional contact with the surface to be cleaned.

While the blades 15 and 16 are made of flexible material, they have sufficient rigidity to prevent the free portions 20 from assuming a position which is in line with the intermediate flat portions of the blades and thus prevent the working edges of the blades from being dragged over the floor rather than having its usual frictional engagement with the working surface when the free portions 20

of the blades are at right angles to the surface to be cleaned.

Having thus described my invention, I claim:

- 5 1. A surface cleaning device comprising a block, a plurality of closely associated flexible blades secured to the block, the portions of the blades free of the block being concavo-convex in cross section and extending forwardly of the block, said concavo-convex blades cooperating with each other to cause the free ends of the blades to maintain a positive contact with the floor.
- 10 2. A surface cleaning device comprising a block, a plurality of closely associated flexible blades secured to the block, the portions of the blades free of the block being concavo-convex in cross section and extending forwardly of the block, said concavo-convex blades cooperating with each other to cause the free ends of the blades to maintain a positive contact with the floor, and means for slightly spacing the free portions of the blades from each other.
- 15 3. A surface cleaning device comprising a block, a plurality of closely associated flexible blades secured to the block, the portions of the blades free of the block being concavo-convex in cross section and extending forwardly of the block, and a wire located be-
- 20
- 25
- 30

tween the blades at points adjacent the edges of the block for slightly spacing the blades from each other.

4. A surface cleaning device comprising a block, a plurality of closely associated flexible blades secured to the block, the free portions of the blades projecting from the adjacent edges of the block and curved outwardly from said block whereby when the working edges are applied to a surface to be cleaned the curved portions will cooperate with each other to assume a substantially right angular position with respect to the surface so that the working edges will frictionally engage such surface.

5. In a surface cleaning device comprising an oblong block, a plurality of closely associated flexible blades having flat portions in engagement with the longitudinal outer surface of said block, the blades being provided with portions extending beyond the longitudinal edges of the block and curved outwardly from said block, a cleat extending longitudinally of the blades, means for securing the cleat and likewise the blades in rigid engagement with the block, and a wire extending around the block and between the blades for slightly spacing the blades from each other.

WILLIAM B. LYNCH.
